UNITED STATES PATENT OFFICE

CHESTER L. BRISTOL, OF ELYRIA, OHIO

ELECTROTHERMAL STARTING CARBURETOR

Application filed June 5, 1926, Serial No. 113,629. Renewed March 1, 1929.

This invention relates to priming or starting devices for internal combustion engines, especially motor vehicle engines, and particularly to means for supplying a gaseous explosive mixture to such engines.

Many attempts have heretofore been made to provide priming or starting devices of the general character to which this invention relates, but these, for the most part, have failed, for one reason or another, to be efficient and practical.

In order to effectively start an internal combustion engine when cold, especially in winter weather, it is necessary to supply to the cylinders a non-condensing rich mixture of fuel vapor and air. It is not ordinarily sufficient, as heretofore proposed by many, to inject liquid fuel into the cylinders or intake manifold. Neither can the best results be obtained by vaporizing the fuel and immediately allowing the undiluted vapor to come into contact with cold surfaces, on which it will quickly condense.

Prior investigators have heretofore proposed to supply liquid fuel to a heating device and then conduct the vaporized fuel from such heating device to the engine. Such investigators have, however, for the most part, lost sight of the fact that the vaporization of the fuel in the heating device generates a very appreciable back pressure, which would, in many cases, shut off the flow of liquid fuel to the heating device, and thus seriously reduce the supply of vapor at the very moment when it is most needed.

I have discovered that in order to effectively supply an abundant flow of explosive mixture to the engine at starting, it is necessary not only to employ a heating device, but also to provide a pump for positively forcing the fuel into and through the heating device, so as to overcome the back pressure above referred to, and maintain a continuous stream of fuel.

Furthermore, I find that, by providing means for confining the pressure due to the vaporization of the fuel, and preventing it from escaping backwardly in the direction from which the liquid fuel came, I can utilize such pressure to force the vaporized fuel out

of the heating device into the engine. Thus the pressure due to the vaporization and superheating of the fuel in the heating device serves to cause a positive flow of gaseous mixture into the engine, entirely independent of the suction of the engine, or even of the pump. This feature is especially advantageous in cold weather, when the engine is stiff, and when it is frequently impossible to rotate it fast enough to produce the suction necessary to draw in an adequate supply of fuel.

I also propose to prevent the condensation of the vaporized fuel issuing from the heating device by mixing the vapor with air, as fast as it issues, thus producing a carbureted or explosive mixture which has the properties of a permanent gas, and from which the fuel particles will not readily condense when they come into contact with the cold walls of the engine.

Electric heating devices for use in apparatus of the above character have been heretofore proposed, but in many cases, the designers appear to have failed to grasp the principles on which economy and efficiency of such a device should be founded. I find that, in order to conserve time and electrical energy, it is necessary to substantially isolate the heating element and fuel from any surrounding masses of metal or other material, so that no heat can be transferred from such element or fuel by conduction. In this way, all of the heat generated is available for vaporizing and superheating the fuel.

One of the important features of the invention consists further in the provision of a specially designed heating device, this device comprising a small tube of electrically conducting material, through which tube the fuel is led, while an electric current is also passed through the tube, thus heating the same and vaporizing the fuel.

In addition to the improved heating element, the present invention seeks to provide the improved air mixing or carbureting device above referred to, and an improved pumping mechanism for positively forcing the fuel into and through the heating device.

In order that the invention may be readily understood, reference is had to the accom-

panying drawing, forming part of this specification, and in which:—

Figure 1 is a vertical sectional view through my improved starting device, parts being shown in elevation, and the electrical circuits employed in connection therewith and with the starting motor being also indicated;

Figure 2 is a fragmentary diagram illustrating a modified arrangement of circuits which can be employed; and

Figure 3 is a fragmentary transverse section through the circuit controlling mechanism shown at the upper part of Figure 1.

Although in its broader aspects, any kind of a pump either manual or power operated, may be employed, I prefer, as a matter of convenience and efficiency, to employ an electro-magnetically operated pump. In the embodiment shown in the drawing, this comprises a cylindrical casing 1, connected with upper and lower heads 2 and 3, all preferably being of magnetic material, and enclosing an insulating spool 4 on which is wound a bobbin of insulated wire 5, constituting a solenoid. This solenoid is provided with a movable core 6, which preferably operates vertically, as shown. To the lower end of this core is rigidly secured a disc 7, which constitutes the piston of the pump. This piston snugly fits and reciprocates within the upper portion of a tube 8, preferably formed of brass or the like, and having a bore which constitutes the cylinder of the pump. This tube 8 is threaded at its upper end into a similarly threaded boss 9, formed on the lower head 3.

The lower part of the tube 8 is bored out to somewhat larger diameter than the upper part, so as to form a shoulder 8^a between the two bores. Fitting within the larger bore and seated against the shoulder 8^a is a cylindrical block 10, which constitutes the head of the pump. This block has a laterally extending port 11, which communicates with a pipe line 12, leading from the fuel reservoir (which may be either at a higher or lower level than the pump). The port 11 opens upwardly into the pump barrel and is controlled by means of a downwardly closing ball check valve 13. This constitutes the inlet valve of the pump. The outlet from the pump is by way of a port 14, formed in the block 10, and controlled by an upwardly closing ball check valve 15, which is confined to its place by a wire netting or other suitable cage 16. In a central socket in the upper face of the block 10, above the ball 13, is screwed a plug 17, having a central opening or port through which liquid flowing past the check valve 13 passes into the pump barrel. When the pump is idle and in its normal position, the port in the plug 17 is closed by means of a cone-shaped valve 18, mounted to reciprocate in a pocket or recess formed

in the lower end of the core 6 and urged downwardly by means of a light helical spring 19, mounted above the same. Thus, the valve 18 is held to its seat by this spring, and normally serves to shut off communication between the pipe 12 and the interior of the pump, so that when the pump is idle, no fuel can leak past the valve 13 into the heating device hereinafter described. The piston 7 and core 6 are moved to and maintained in the normal position shown in the drawings by a relatively strong helical spring 20, which surrounds the lower end of the core 6 and is interposed between the head 3 and the piston 7.

Fitted within the tube 8 below the block 10 and extending nearly to the bottom thereof is a sleeve or lining 21 of magnetic material. The purpose of this will hereinafter appear. Set into this sleeve at a point slightly below the block 10 in a disc or plate 22, also of magnetic material, and carried by this plate and depending centrally in the sleeve 21 is a cylindrical bar or core 23, of magnetic material.

My improved heating element consists of an electrically conducting tube of small bore, preferably formed of some relatively high resistance material such as nichrome alloy. The upper end of this tube is secured to the block 10 at a point below the valve 15. The tube then passes down through an opening in the disc 22, and is coiled around the core 23 in the form of a helix, as indicated at 24. The lower end 26 of the tube extends downwardly through an insulating bushing 29^a set into a plug 30, which closes the lower end of the tube 8. This plug carries a depending hollow boss 29, into the lower end of which is threaded one end of a tube or conduit 27, which is then bent laterally and extends, as indicated at 28, to the engine, where it is connected to a suitable part thereof, such as the manifold 33.

It will be observed that the helix 24 is considerably smaller than the sleeve 21, which surrounds it, so that it is spaced a substantial distance from such sleeve. It is also spaced a considerable distance from the core 23, around which it is coiled. In other words, it will be observed that the entire helix from the plate 22 to the bushing 29^a is out of contact with any solid mass so that the loss of heat from said helix by conduction is avoided.

The plug 30 is provided with a plurality of ports 31 extending vertically therethrough, some of these ports being outside and some inside of the hollow boss 29. Both sets of ports are covered by an annular valve plate 32, which normally rests upon the upper surface of the plug 30, and within a short distance of the lower ends of the sleeve 21 and core 23. The plate 32 is of magnetic material.

From the above, it will be seen that when

current passes through the helical tube 24, the magnetic flux generated thereby and operating through the disc 22, sleeve 21 and core 23 will serve to lift the magnetic valve plate 32 from its seat, and thus establish communication between the inner and outer sets of ports 31. When the plate 32 is thus raised, and these ports open, it will be seen that air can flow upwardly through the outer 10 ports into the tube 8 and thence downwardly through the inner ports into the hollow boss 29. The interior of this boss and the adjacent end of the tube 27 thus constitute a carbureting or air mixing chamber in which the vapor 15 issuing from the lower end 26 of the tube is mixed with air as fast as it flows out. It will be further noted that the jet of vapor issuing from the lower end of the tube produces an injector action in the tube 27, which serves 20 to draw air in through the ports 31, and the mixture of air and vapor, which is stable and does not readily condense, is then forced through the tube 28 into the engine manifold and cylinders, where it is readily ignited.

25 Mounted on the upper end of the solenoid case is a block 34 of insulating material to the side of which is pivoted, by means of a screw 35, a switch lever 36, adapted to move into and out of engagement with a contact 37, also carried by the block 34. The switch lever 36 is moved on its pivot by means of a pair of lugs or collars 39, of insulating material, secured to a rod 38, set into the upper 30 end of the core 6, and freely slidable through 35 the head 2 of the solenoid casing. In order to cause the switch lever 36 to remain temporarily in any position to which it may be moved, I apply to such lever a frictional drag by means of a spring 40, surrounding the 40 screw 35, and bearing against the lever, as shown in Figure 3. It will be noted that the collars 39 are spaced apart a distance considerably greater than the width of the lever 36, so that there is a large amount of 45 lost motion between the rod 38 and such lever. In other words, the lever is moved only toward the end of the stroke of the rod 38, in either direction.

50 My improved fuel supplying device, as above described, is adapted to be used in connection with motor vehicles equipped with the usual storage battery and starting motor. The battery is indicated at 41, and one side of it is grounded, as usual, as shown 55 at 42. In order to render the circuits easily traceable, I have also shown this same side of the battery as connected at 43 to the frame or casing of the solenoid.

44 designates the usual starting switch, 60 and this is connected by means of a wire 45, with one terminal of the starting motor 46, the other terminal of which is grounded. 48 designates the usual ammeter, and a wire 47 connects the ungrounded side of the battery through this ammeter with a manually 65

operated switch 49. This switch is arranged to selectively engage three contacts, 50, 51 and 52. The contacts 50 and 51 are connected by a wire 56, and a wire 53 extends therefrom to an insulated binding post 54, carried by the boss 29. A clip or connector 55 extends from the binding post 54 to the lower end of the tube 24. The other end of this helical tube is in electrical contact with the frame of the device, and is thus grounded. 70

A wire 57 extends from the contact 52 to a binding post 58, carried by the block 34 and this binding post is connected by means of a wire 59 with the contact 37.

The inner end of the solenoid winding 5 is 80 connected as indicated at 60 with the screw 35 and lever 36, while the other end of the solenoid winding is grounded on the frame, as by means of a spring terminal 61, engaging the head 2.

The operation of my improved device will now be briefly described. When it is desired to start the engine, the switch 49 is first swung over to the left into engagement with the contact 50. This establishes a circuit from the battery 41 through the ammeter 48, switch 49, contact 50, wire 53, binding post 54, connector 55, helical tube 24, to the frame of the device and thence back to the other side of the battery. The current flowing through this circuit will have the effect of strongly heating the tube 24. After the switch 49 has remained on the contact 50 for a few seconds, it is swung over to the right, into a position where it simultaneously engages both contacts 51 and 52. The contact 51 serves to maintain the circuit just traced, so that current continues to flow through the helical tube 24. At the same time, current flows from contact 52 through wire 57, and binding post 58, to contact 37, over lever 36 and wire 60 to and through the winding of solenoid 5, from which it passes back to battery. This energizes the solenoid 5 and causes the core 6 to be drawn upwardly. Just before the core reaches the upward limit of its stroke, the lower collar 39 engages under the switch lever 36 and swings it upward out of engagement with the contact 37, thus breaking the circuit through the solenoid and de-energizing the same. Immediately that the solenoid is de-energized, the spring 20 forces the core 6 down again, and before the lower limit is reached, the upper collar 39 engages the switch lever 36 and swings it again into engagement with the contact 37. This again energizes the solenoid and the cycle is repeated, the core 6 continuing to reciprocate as long as the circuit through contact 52 is closed. Thus, the pump piston 7 is moved up and down in the tube or barrel 8, and liquid fuel is drawn in through the pipe 12, and forced down into and through the heated helical tube 24. As the fuel passes through

100 the tube, it is not only vaporized, but super- 105 110 115 120 125

heated to a high degree, and the hot vapor is discharged from the lower end 26 of the tube under considerable pressure, and in copious quantity. The valve plate 32 meanwhile having been lifted by the magnetic effect of the current in the helical tube 24, air is drawn into the mixing chamber adjacent the nozzle 26 and thus mixed with the superheated vapor, the hot mixture being then forced through the tube 28 and delivered continuously to the engine manifold. It will be noted that the ball 15 operates as a check valve to prevent the backward flow of vapor, and the pressure due to vaporization and superheating of the fuel is thus confined in the heating tube. This pressure causes the gasified fuel to be forcibly ejected from the lower end 26, of the tube, as above described.

Practically simultaneously with throwing the switch 49 into engagement with the contacts 51 and 52 as described, the operator may depress the starting switch 44, thus causing the starting motor to crank the engine. Owing to the abundant supply of a warm, rich, non-condensing explosive mixture in the manifold, the engine will start immediately, and without the necessity for prolonged operation of the starting motor.

While I have shown and described one arrangement of circuits for operating my improved device, it is obvious that other arrangements can be employed. One such modified arrangement is illustrated in Figure 2, in which, instead of the switch 49 and its associated contacts, I employ a switch 62 of the push button type, this switch being connected with the battery by wire 63 and, when depressed, serving to establish connection between the battery and the wire 53. In this arrangement, the wire 57 is connected by wire 64, with the wire 45 leading to the starting motor.

The operation is as follows. When it is desired to start the engine, the operator first depresses switch 62 for a brief interval of time. This supplies current from the battery through the wire 53 to the helical tube, thus causing the same to warm up. After a few seconds, the starting switch 44 may be depressed. Upon closure of this starting switch, current is supplied not only to the starting motor, but simultaneously through the wires 64 and 57 to the pump solenoid, the flow of current being maintained through the heating tube by continuing to hold down the switch 62. Thus, the tube is heated, the pump operated, and the starting motor set in motion at the same time, and the engine should immediately start.

What I claim is:—

1. A fuel gasifying device for starting internal combustion engines comprising an electrically conducting tube, means for passing an electric current through said tube to heat the same, a connection at one end of the

tube for supplying liquid fuel thereto, an air mixing chamber into which the other end of said tube delivers, means for connecting said chamber with the engine, and means operated by the flow of current through said tube for controlling the supply of air to said chamber. 70

2. A fuel gasifying device for starting internal combustion engines comprising an electrically conducting tube wound in the form of a helix, means for passing an electric current through said tube to heat the same, means for supplying liquid fuel to one end of said tube, an air mixing chamber into which the other end of said tube delivers, means for connecting said chamber with the engine, and a valve operated by the magnetic flux set up by the current in said helical tube for controlling the supply of air to said chamber. 75

3. A fuel gasifying device for starting internal combustion engines comprising a heater through which the fuel is caused to pass, means independent of the engine and including an automatically operated shut off valve for mixing the vaporized fuel with air as soon as it issues from said heater, to prevent condensation thereof, and means for delivering the mixture of fuel vapor and air to the engine. 80

4. A priming device for internal combustion engines comprising a tube, means for causing liquid fuel to flow into one end of the tube, means for heating said tube to vaporize such fuel, means whereby the pressure due to vaporization is prevented from stopping the flow of fuel into said tube, and means for delivering to the engine the vaporized fuel forced from the other end of the tube by the pressure generated therein by vaporization. 95

5. A priming device for internal combustion engines comprising a tube, means for heating said tube, a continuously operating power actuated pump for positively forcing liquid fuel into and through said tube and for building up an effective pressure to overcome the back pressure due to vaporization of the fuel in the tube and thus maintain a constant flow, and means for delivering to the engine the vaporized fuel forced from said tube by said pump and vaporization pressure, said tube being located between the pump and engine. 110

6. Means for furnishing an explosive mixture to internal combustion engines at starting, comprising an electric heating device, an electrically operated pump for positively forcing fuel into and through said heating device to vaporize the fuel, means for delivering the vaporized fuel to the engine, and means for simultaneously supplying current to both the heating device and pump. 115

7. Means for furnishing an explosive mixture to internal combustion engines at starting, comprising an electric heating device, a 120

reciprocating pump, a solenoid for continuously reciprocating said pump to positively force fuel into and through said heating device to vaporize the fuel, means for delivering to the engine the vaporized fuel issuing from said heating device, and means for simultaneously supplying said heating device and solenoid with current.

8. In starting mechanism for internal combustion engines, the combination with a starting motor, of an electric heating device, a reciprocating pump for supplying fuel into and forcing it through said heating device to vaporize the fuel, electromagnetic means for operating said pump, means for delivering to the engine the vaporized fuel issuing from said heating device, means for simultaneously supplying current to said starting motor, heating device and electromagnetic means, and independent means for supplying current to said heating device to warm it up before the motor is started.

9. Priming apparatus for internal combustion engines comprising a heating device, a pump for forcing liquid fuel into and through said heating device to supply an explosive mixture to the engine, said pump having the usual inlet and outlet valves, power means for continuously operating said pump as long as desired, and automatic means in addition to said valves, serving, when the operation of said pump is discontinued, to shut off the flow of liquid fuel to said heating device.

35 10. Starting apparatus for internal combustion engines comprising a heating device, means for supplying liquid fuel into said heating device, and means whereby the expansion of hot, gasified fuel issuing from said heating device will cause such fuel to enter the engine intake and cylinders under pressure, even before the engine begins to move.

11. A fuel gasifying device for starting internal combustion engines comprising a heater through which the fuel is caused to pass so as to be vaporized, an air mixing chamber into which the vaporized fuel is discharged as it issues from said heater, said air mixing chamber communicating with the engine, and means controlled by the operation of said heater for governing the supply of air to said mixing chamber.

12. A fuel gasifying device for starting internal combustion engines comprising a tube, means for heating said tube by means of an electric current, a connection at one end of the tube for supplying liquid fuel thereto, an air mixing chamber into which the other end of said tube delivers, means for connecting said chamber with the engine, and means operated by the flow of heating current for controlling the supply of air to said chamber.

In testimony whereof I affix my signature.
65 CHESTER L. BRISTOL.
